UNITED STATES PATENT OFFICE.

GEORGE LAKINS, OF EAST NORWALK, AND LESTER N. LAKINS, OF TOLEDO,
OHIO.

IMPROVEMENT IN WIRE FENCES.

Specification forming part of Letters Patent No. 142,246, dated August 26, 1873; application filed
August 8, 1873.

To all whom it may concern:

Be it known that we, GEO. LAKINS, of East Norwalk, Huron county, Ohio, and LESTER N. LAKINS, of Toledo, Lucas county, Ohio, have invented certain new and useful Improvements in Wire Fences, of which the following is a specification:

Our invention relates to improvements in wire fences; and consists of devices which will be hereafter fully described and claimed.

The accompanying drawings represent a fence with our improvements.

The flanged posts are represented at *a*. These have wedge-shaped holes 2, through which the wires pass. A key, 3, presses the wires into the small part of the hole, and thus prevents the wire from slipping. The corner or end post is provided with a brace, *c*, the upper end of which has a notch resting in another notch in the flange of the post. The lower end of the brace rests upon a stone, *e*, or in a groove in the stone or bed-piece. It is provided with an adjustable rod and nut, *g*. This brace counteracts the strain of the wires, thus holding the post in an upright position. A rail is placed upon the top of the fence, a groove being cut in its under side, so that it will ride the top wire. This rail *i* may be fast-

ened to the flanged post by a bolt. The upper ends of the stays are split, and then clinched down upon the ends of the rails, as seen at 5, and a bolt, pin, or nail may be put into the rail and clinched; also, a strip of band-iron may be tacked on top of the rails to hold the joint and keep it dry.

If extra strength is desired, two top wires may be used, being placed at equal height and on opposite sides of the flanged posts and stays.

Having thus described our invention, we claim—

1. The combination of the post *a*, the brace *c*, adjustable rod *g*, and stone *e*, substantially as shown and described.
2. The stays 4, split at top, as shown at 5, and bent in opposite directions to clinch the grooved ends of the cap-rail, substantially as shown and specified.

GEORGE LAKINS.
LESTER N. LAKINS.
